UNITED STATES PATENT OFFICE.

SAMUEL PEACOCK, OF CHICAGO, ILLINOIS, ASSIGNEE TO INTERNATIONAL AGRICULTURAL CORPORATION, OF NEW YORK, N. Y., A CORPORATION OF NEW YORK.

PROCESS OF MAKING COMPOUNDS IN ELECTRIC FURNACES.

1,129,513.

Specification of Letters Patent. Patented Feb. 23, 1915.

Application filed September 22, 1913. Serial No. 791,129.

To all whom it may concern:

Be it known that I, SAMUEL PEACOCK, a citizen of the United States, residing at Chicago, in the county of Cook and State of Illinois, have invented certain new and useful Improvements in Processes of Making Compounds in Electric Furnaces; and I do hereby declare the following to be a full, clear, and exact description of the invention, such as will enable others skilled in the art to which it appertains to make and use the same.

This invention relates to a process of producing compounds in electric furnaces and has for one of its objects to render more efficient similar processes heretofore proposed.

With this and other objects in view the invention consists in the novel combinations of steps constituting my process as will be more fully hereinafter disclosed and particularly pointed out in the claims.

In order that my process may be more clearly understood, reference is had to a furnace suitable for carrying out my invention, which is illustrated in the accompanying drawings forming a part of this specification in which like numerals designate like parts in all the views:

30 Figure 1 is a sectional view of a furnace built in accordance with my invention; and, Fig. 2 is a sectional view, taken on the line 2—2 of Fig. 1.

1 indicates the electrodes, which are preferably two in number and of a built-up construction, as shown.

2 indicates the body of the furnace, which may be of brick work or other insulating material; 3, a steel jacket for said body portion; 4, a metal section forming a continuation of the furnace shaft and chamber; 5, valved conduits for leading off the exit gases; 6, a continuation of the section 4 provided with the hand feed opening 50; 45 7, a section bolted to the member 6; 8, a rotating gate or valve forming a gas tight connection with the furnace chamber and adapted to feed measured quantities of charge material 9 to the furnace chamber 50; 50 10 which is preferably tapered toward the bottom, as shown; 11 indicates oppositely disposed valved inlets for nitrogen, or producer gas, located below the electrodes 1, and preferably passing through the reduced

portion 13 of the furnace body, as shown. 55 Said reduced portion 13 is also provided with a steel casing 14, and its lower end opens into the conduit or delivery passage 15, preferably provided with the screw conveyer 16, and outlet or delivery 17, adapted 60 to pass the material into any suitable receiver, not shown. Any suitable means for rotating the conveyer 16 may be provided, and 19 is a gear for rotating the rotating valve or feed member 8. 56

The furnace chamber 10 is preferably square, or almost square in cross section, and the area of each of the opposed exposed faces of the electrodes is preferably made at least as great as the area of said 70 section, so that the path of least resistance through the molten material will be practically directly from one electrode face to the other; and therefore, the objectionable short circuiting and deflections of the current through said material, with the consequent unequal heating thereof, now so annoying in furnaces of this type, are largely, if not entirely done away with. This, I consider an important feature of my invention, 75 and is conveniently secured by building up the electrodes 1 from slabs of graphite, as shown. The furnace is gas tight, when operating, as will be clear from the drawings, and by oppositely disposing the gas inlets 85 11 as illustrated, and thus causing the streams to meet in the middle of the charge, an even and steady flow of nitrogen through the reaction zone is had, which would not be the case if only one inlet was employed. 90

The operation of my furnace will be clear from the foregoing, but may be briefly summarized as follows:—The chamber 10 may be filled with coke up to the electrodes, and then hot coke thrown in through the opening 5, the current turned on and the conveyer started while charge material is fed down through the chamber; or the said chamber may be filled with coke to a point above the electrodes, the current turned on 95 and when the coke becomes incandescent, it may be fed out through the conveyer while charge material is caused to follow down into the reaction zone. In either case, the turning of the feed valve or member 8 100 will cause charge material 9 to be uniformly fed to the reaction zone, and the turning of the screw conveyer 16 will cause

the product to be uniformly removed from said zone.

The current, in furnaces of this type, as is well known, has heretofore been exceedingly difficult to control, it being stronger through some parts of the charge than through others, and it has resulted from this that the heating of the charge has not been uniform and the product as a consequence has been irregular in quality. In my invention, however, not only does the large area of the electrode faces above mentioned serve to remedy this grave defect, but I also preferably briquet my charge material 9, 15 so that the original uniform distribution of conducting material is maintained in the reaction zone, and the current accordingly remains more steady than heretofore. Not only do I thus steady the current through 20 the reaction zone, and therefore produce a more uniform temperature and product, but I also regulate the amount of current that flows through the reaction zone, and therefore the amount of heat generated therein, 25 or the temperature of said zone, by regulating the amount of carbon in the charge. It follows from this that I may so regulate the amount of carbon in the charge as to produce a temperature of only say 1500° C. 30 in the reaction zone, which would be suitable for producing calcium carbo-nitrid $\text{Ca}_2\text{N}_2\text{C}_3\text{N}_4$, for example, or I may put in less carbon and thus raise the temperature to 1900° C. and thus produce a temperature 35 suitable for making a nitrid such as Ca_3N_2 , from the same charge material. But, the above principles of operation are adapted for the fixation of atmospheric nitrogen whether one employs oxids, sulfids, etc., of 40 metals, metaloids, or non-metals. They are also adapted for causing other chemical combinations in a manner more efficient than heretofore, all as will now be explained.

It is well known that a large number of 45 chemical elements will combine with nitrogen to form nitrids if the conditions of temperature are favorable, and under varying conditions of treatment there may be formed double nitrids, such as cyano-nitrids, carbo-nitrids, silico-nitrids, sulfo-nitrids, phospho-nitrids, etc. Further, it is known that theoretically at least oxygen and calcium nitrids may be produced by heating calcium oxid in an atmosphere of 50 nitrogen up to say 4000° C.; but these nitrids under these conditions are usually decomposed as fast as they are formed. On the other hand, if we cause the oxygen of the calcium or other oxid to combine with 55 carbon, or sulfur, etc., and to be removed from the zone of reaction as fast as formed, then the metal, metaloid, etc., will also combine with carbon or sulfur, etc., to form a carbid, or a sulfid, etc. Further, these carbids or sulfids thus formed are capable of

dissociation in the presence of gaseous nitrogen to form nitrogen compounds according to the following illustrative equations:—

and

In fact a little consideration will show that if R represents a metal, a non-metal, or a metalloid radical, the principle of the above equations hold in all RO , RS and similar relations. But in applying these general principles to commercial needs several limitations are at once encountered. The carbids, oxids, sulfids, etc., must be exposed to free nitrogen at the requisite temperatures and in such a manner that no oxygen (O) or gas containing oxygen such as carbon dioxid (CO_2), water vapor (H_2O), etc., may be present. Further, the exclusion of these gases must not materially increase the cost of the product. Now all of these conditions are fulfilled by my process in the fixation of free nitrogen because, by attaching a suction or other apparatus to the pipes 5, and by regulating the valves in 95 said pipes I can make the internal pressure whatever may be desired, by regulating the amount of carbon in the charge I can make the temperature whatever may be desired, and by keeping the voltage of the current 100 down to say 40 or 50 volts, I can prevent any appreciable arcs from forming and abnormally heating the charge in spots. This will all be clearer upon considering the following concrete example:—Suppose it is 105 desired to form a double nitrid of phosphorus and calcium from a mixture of phosphate rock and finely divided coke and coal, and that the temperature should be maintained at about 1400° C. The charge is made up with 70 110 to 75% of carbon, briqueted and fed to the furnace whereupon with a current of about 50 volts, and a furnace having a chamber twenty inches square, and complying with the above disclosure, the above temperature 115 will be found to be produced in the reaction zone. Again, suppose it is desired to produce a double nitrid of magnesium and carbon, and that the temperature should not rise above 1500° C., a suitable mixture of 120 magnesium oxid MgO and finely divided carbon is made up and the mixture made to contain 65% to 70% of carbon. On the other hand, if a temperature of 1900° C. to 2000° C. is desired for the making of a calcium or a magnesium nitrid instead of the carbonitrid from the above charges, then the carbon content must be reduced to say 125 40% to 45% carbon.

The proper quantity of carbon in each in- 130

stance to produce the required temperature is determined by experiment and tabulated for future use.

By the above process, I am enabled to fix 5 nitrogen as a carbo nitrid RCN_2 instead of a nitrid R_2N_2 , and this therefore enables me to fix the nitrogen at a lower temperature, as well as to fix three times as much nitrogen as would be possible if the temperature was 10 permitted to rise high enough to dissociate the said carbo-nitrid, and thereupon form a nitrid. But, again, under some circumstances, it is more desirable to fix the nitrogen as a nitrid, and when these conditions 15 exist, my process enables one to readily accommodate the plant to the existing requirements. When synthesizing other compounds, the same general remarks apply and it is therefore not deemed necessary to discuss 20 a special example.

Especial attention is called to the fact, that by employing a very large percentage of conducting carbon in the charge, the temperature of said carbon when considered 25 alone, will be practically constant, notwithstanding its motion past the electrodes; and the heat radiated from this carbon alone is a large factor in maintaining the temperature of the mineral portion of the charge 30 material constant. In addition to this the said mineral portion of the charge material being in a comparatively small proportion, it is highly heated from this large proportion of carbon and rendered more uniform 35 in its conductivity, so that it does not disturb the even flow of current in its motion past the electrodes to the extent that has been the case heretofore. In other words, my carbon really constitutes a moving resistor 40 more or less mixed with mineral charge material; and it is evident from the above disclosure that by properly proportioning the amount of carbon and the amount of mineral charge material, (the voltage remaining constant), that any desired high or low constant 45 temperature may be at once attained. On the other hand, this result is conveniently attained by also so manipulating the voltage and amperage as to produce this said temperature.

50 What I claim is:—

1. The process of producing compounds containing nitrogen in an electric furnace which consists in preparing a charge 55 containing carbon; regulating the amount of carbon in the charge according to the tem-

perature desired in the reaction zone; passing said charge through said reaction zone in the presence of free nitrogen; and maintaining the voltage of the current at a value 60 too low to permit substantial arcs to be formed, substantially as described.

2. The process of producing compounds containing nitrogen in an electric furnace which consists in preparing a charge 65 containing carbon; regulating the amount of carbon in the charge according to the temperature desired in the reaction zone; passing said charge through said reaction zone in the presence of free nitrogen; drawing 70 off the gaseous products of the reaction as fast as they are formed; withdrawing the finished product from the furnace as fast as it is formed; and maintaining the voltage of the current at a value 75 too low to permit substantial arcs to be formed, substantially as described.

3. The process of producing compounds containing nitrogen in an electric furnace provided with oppositely disposed electrodes 80 which consists in preparing a charge containing carbon; regulating the amount of carbon in the charge according to the temperature desired in the reaction zone; passing said charge while having a cross section 85 substantially equal to the cross section of said electrodes through said reaction zone in the presence of free nitrogen; drawing off the gaseous products of the reaction as fast as they are formed; withdrawing the finished product as fast as it is produced; and maintaining the voltage of the current at a 90 value too low to permit substantial arcs to be formed, substantially as described.

4. The process of producing uniform 95 products in an electric furnace which consists in passing a predetermined quantity of conducting resistor material through a reaction zone; passing a predetermined quantity of charge material mixed with said resistor material through said reaction zone; in maintaining the voltage of the current 100 too low to permit of any substantial arcing; and in regulating the amperage to produce the required temperature, substantially as 105 described.

In testimony whereof I affix my signature, in presence of two witnesses.
